UNITED STATES PATENT OFFICE

ALFRED RISTOW, OF BERLIN-NEW COLOGNE, GERMANY

RADIO RECEIVING SYSTEM

Application filed February 27, 1928, Serial No. 257,224, and in Germany February 22, 1927.

An application was filed in Germany, February 22, 1927.

The present invention relates to radio receiving systems in which the point at which reception actually occurs is remote from the apparatus affected by the aerial radiations.

It has been found that owing to well-known causes of various kinds, it is impossible to install receiving installations which should

10 be capable at any moment of receiving messages in cities. Examples of such installations are subscribers to a press service, stock exchange service or weather service and receiving installations of public authorities.

15 All these installations must be capable at any moment of receiving in a reliable manner the messages intended for them, as on the one hand dependence is placed on them and on the other hand such messages are mostly sent

20 only once. In order to ensure adequate reception, such receiving installations must be located out of towns, the reception room in the town being connected to the receiving installation by means of a telephone line.

25 The drawback of this arrangement is that it is necessary to have a special staff for the receiving apparatus who have nothing to do but to tune it, whilst the messages are received by the staff in the town. The conditions are similar in all cases in which the transmitting and receiving installation is to be worked from a central station. In order to avoid disturbance by the transmitter, it is necessary to arrange the receiving installation

30 separately and spaced from the transmitter or from the central working station.

According to the invention, these drawbacks are avoided by a remote electrical control of the receiving apparatus which is ef-

40 fected by means of the transmission line. In order to guarantee reliability of reception even in the event of a valve burning out, two or more receiving apparatus which can be switched in and out at will by means of the

45 said remote control are provided. The cost of the second receiving apparatus is compensated for many times by economy in the attendant staff.

50 One way of carrying the invention into effect is diagrammatically illustrated by way

of example, in combined Figures 1 and 1a of the accompanying drawings, while Figure 2 shows a feature appearing in Figure 1 more in detail.

The arrangement depicted comprises two 55 receiving apparatus E1 and E2 with a single-knob control constructed in such a manner that by turning the tuning knob from the zero mark on the scale the aerial and the heating circuit are switched in. It 60 will be shown later on that one receiver can be worked only after the other one has been switched off. The telephone leads T1 and T2 are connected to the winding W1 of the ring repeater U1, the secondary winding of 65 which is tapped in the centre, whilst to the outer ends the transmission lines L1, L2 are connected and lead to the tapped winding W3 of the ring repeater U2, the secondary winding of which contains a telephone T or 70 other signal reproducing apparatus.

For effecting the remote control, two three-pole control keys St1 and St2 are provided. The negative pole of the battery B1 is connected to the contacts *a* of the two 75 keys, the contacts *c* to the positive pole, whilst the contact *b* of the key St2 is connected to earth and the contact *b* of the key St1 to the tapping of the winding W3, with the interposition of a milliammeter MA. 80 When the key St1 is depressed, the positive pole of the battery will be connected to the line and the negative pole to earth, but when the key St2 is depressed, the positive pole will be connected to earth and the negative 85 pole to the line. By depressing the two keys as desired it is therefore possible to send currents into the transmission line in either direction.

The tapping of the winding W2 of the 90 ring repeater U1 is connected to earth with the interposition of a resistance R and of a two-pole relay MR so that, by this circuit, the control circuit is closed through the earth. At the same time the circuit is also closed 95 through the resistance R and through the relay R_t to earth. According to the direction of the control current, the relay MR will be thrown over in one direction or the other and in that way a series motor HM, 100

which effects the tuning of the receivers, is correspondingly connected to the battery B2 and its direction of rotation determined accordingly.

5 The mechanical arrangement will be explained first for the receiver E2:—The tuning knob K of the receiver E2 is connected, with the interposition of various gear wheels, to the movable part of a clutch magnet TM2, to which current is supplied through two slip rings 1 and 2. The driving spindle of the clutch magnet engages, by means of another gear wheel, with the gear wheel Z which is mounted on the same 10 spindle as the resistance R and the operating wheel Sch of a three-pole switch DR driven by the series motor HM with the interposition of worm wheels or other gearing. The resistance R comprises an annular winding which is rigidly secured to the spindle, whilst current is supplied through the slip ring 3 and the brush 4.

The three-pole switch DR is shown in detail in Figure 2. On the operating wheel 25 Sch two stops or tappets are mounted one at each side and suitably displaced relatively to each other. When the operating wheel is turned clockwise, as assumed by way of example in the drawings, the lever H1 of the 30 three-pole switch will be rocked and brought into the position shown in dotted lines until it engages with a spring F1 mounted on a magnet, the winding of which is always excited. The construction in the present example is such that the spring is magnetized and is in a position to hold the lever H1 in the 35 dotted position, but some other arrangement, say with a permanent magnet, could also be employed. When the operating wheel continues to move in the direction indicated, the 40 spring will be compressed until the stop a1 slides off the lever H1, when the spring will return to its position of rest, but will still hold the lever H1, fast magnetically. The current supply points are the centres of rotation 45 of the lever, and the spring F1. The result of the magnetic retention is that the circuit will not be broken in spite of the operating wheel continuing to rotate, but if the direction of rotation is reversed, the lever H1 will 50 be detached from the spring only at the moment when the stop a1 touches the lever H1, and the contact will be interrupted. The setting of the operating wheel must be such that 55 at the beginning of the contact closing, the clutch magnet TM2 and therefore the tuning device of the receiver E2 which at this moment should be at zero, will be switched on. A rotation of 180° on the tuning scale may 60 correspond for instance to a rotation of 200° of the operating wheel; by a rotation of 200° the whole range of tuning of the receiver E2 will therefore have been traversed. If the operating wheel Sch is turned backwards, 65 then at the moment when the marking 0° on

the tuning scale is reached, the contact by the lever H1 will be broken and the receiver E2 switched off. If the operating wheel continues to rotate in the same direction (that is to say in the direction opposite to that assumed in the drawings), after a short time the stop a2 indicated at the other side of the wheel will strike the lever H2, and therefore the clutch magnet TM1 of the receiver E1 will be switched in. The same thing is repeated 70 as before, with the difference that an increase in the tuning scale reading corresponds to anti-clockwise rotation of the operating wheel and vice versa. This can be easily obtained by a correct arrangement of the transmission gear. In Figure 1 the three-pole switch is shown somewhat differently for the sake of clearness. When the relay MR is thrown over in the manner above described by depressing a key St1 or St2 the motor HM 75 will rotate in a corresponding direction. At the same time the wheel Sch of the three-pole switch will start and close by means of the lever H1 the following circuit:—negative pole of the battery B2, contact of the relay Rt 80 (the relay acts at the moment when the relay MR is thrown over), centre of rotation of H2, contact spring F1, slip ring 1, clutch magnet TM2, slip ring 2, positive pole of the battery. 85

The motor will continue to rotate until the depressed key is released but when the circuit is broken the relay MR will return to the position of rest and the relay Rt will fall off and break the circuit of the clutch magnet. The latter will instantaneously release, whilst the motor has time to run down slowly; if the clutch magnet and the relay Rt were not provided the tuning would be lost again owing to the running down of the motor. 95

If it is desired to pass from the receiver E2 to the receiver E1, first the tuning of the receiver E2 is brought to zero and then the receiver E1 is tuned in a similar manner. 100

It is obvious that the tuning could be effected simultaneously with the listening, and that it is possible to go back with the tuning at will even if the range has been passed. 105

As the resistance R is rigidly secured by a common spindle to the operating wheel of the three-pole switch, to each position of the switch there will correspond a given value of the resistance. As the other resistance values of the circuit, viz., the repeater coil, line and relay MR are constant, the milliammeter MA provided in the listening room, can be calibrated to the position of the operating wheel of the three-pole switch and in that way the tuning of the receivers can be read on the milliammeter. 115

What I claim is:

1. A radio receiving system comprising in combination a receiving apparatus embodying two receivers and a signal reproducing apparatus located at a distance from said 120 125 130

receiving apparatus, a transmission line connecting said receiving and signal reproducing apparatus, means in proximity to said signal reproducing apparatus for sending through said transmission line an electric current, control keys in proximity to said signal reproducing apparatus for varying the direction of said current, a motor responsive as regards direction of rotation to said current, tuning means actuated by a single spindle in each receiver, operative connection between said motor and each of said spindles, a clutch in each of said connections, and means whereby one or the other of said clutches is engaged in accordance with the direction of rotation of said motor.

2. A radio receiving system comprising in combination a receiving apparatus and a signal reproducing apparatus located at a distance from said receiving apparatus, a transmission line connecting said receiving and signal reproducing apparatus, means in proximity to said signal reproducing apparatus for sending through said transmission line an electric current in either direction, tuning means in said receiving apparatus, a motor responsive as regards direction of rotation to said current, an operative connection between said motor and said tuning means, a clutch in said connection, means whereby said clutch is engaged on rotation of said motor in one direction, and means for retaining said clutch in engagement independently of the continuance of said rotation.

3. A radio receiving system comprising in combination a receiving apparatus and a signal reproducing apparatus located at a distance from said receiving apparatus, a transmission line connecting said receiving and signal reproducing apparatus, means in proximity to said signal reproducing apparatus for sending through said transmission line an electric current in either direction, tuning means in said receiving apparatus, a motor responsive as regards direction of rotation to said current, an operative connection between said motor and said tuning means, a clutch in said connection, means whereby said clutch is engaged on rotation of said motor in one direction, means for retaining said clutch in engagement independently of the continuance of said rotation, and means for disconnecting said clutch when said current is stopped or on reversal of said rotation.

4. A radio receiving system comprising in combination a receiving apparatus and a signal reproducing apparatus located at a distance from said receiving apparatus, a transmission line connecting said receiving and signal reproducing apparatus, means in proximity to said signal reproducing apparatus for sending through said transmission line an electric current in either direction,

tuning means in said receiving apparatus, a motor responsive as regards direction of rotation to said current, an operative connection between said motor and said tuning means, a clutch in said connection, means whereby said clutch is engaged on rotation of said motor in one direction, and means responsive to the cessation of said current for stopping said motor and for immediately disconnecting said clutch although said motor continues rotating during a running-down period.

5. A radio receiving system comprising two receivers, a signal reproducer located at a distant point from said receivers, a two-wire transmission line to which said receivers and said signal reproducer are connected, tuning means for each of said receivers, operating mechanism for said tuning means, and remote control means located in proximity to the signal reproducer and controlling over said transmission line said operating means for selecting and tuning either receiver.

6. A radio receiving system comprising two receivers, a signal reproducer located at a point distant from said receivers, a two-wire transmission line to which said receivers and said signal reproducer are connected, a tuner for each of the receivers, operating means for the tuners including a motor rotatable in opposite directions for selecting and tuning the respective receivers, and remote control means located in proximity to the signal reproducer for supplying current of opposite polarity over said transmission line for controlling the direction of rotation of the motor.

7. A radio receiving system comprising in combination two receivers, a signal reproducer located at a distance from said receivers, a transmission line to which the signal reproducer is connected, operating means for the tuners of the receivers including a motor rotatable in reverse directions for actuating said operating means for selectively tuning the respective receivers, coupling devices for automatically connecting the motor with the tuner of one or the other of the receivers on the rotation of the motor in opposite directions, and means for supplying an electric current in either direction through said line to rotate the motor in one direction or the other.

8. A radio receiving system comprising in combination a receiving apparatus including a tuner and a signal reproducing apparatus located at a point distant from said receiving apparatus, a line circuit to which the reproducing and the receiving apparatus are connected, means in proximity to said signal reproducing apparatus for transmitting a current through said line circuit to control the operation of the tuner of the receiving apparatus, means in proximity to said receiving apparatus responsive to said control

current for continuously tuning said receiving apparatus between widely different wavelength ranges, a device variable with the setting of said tuning and located in the path of flow of said control current and operable to vary said current, and an indicator in proximity to said signal reproducing apparatus responsive to said variable current.

9. A radio receiving system comprising in combination a receiving apparatus and a signal reproducing apparatus located at a point distant from said receiving apparatus, a transmission line connecting said receiving and signal reproducing apparatus, means including a plurality of keys in proximity to said signal reproducing apparatus for connecting to said transmission line currents of opposite polarity, operating mechanism including a polar relay responsive to said current for actuating the tuning means of said receiving apparatus, an electrical resistance variable with the setting of said tuning means and located in the path of flow of said current, and an indicating instrument responsive to said current in proximity to said signal reproducing apparatus.

10. A radio receiving system comprising a plurality of receivers, a signal reproducer located at a distance from said receivers, a signal transmission line extending between the receivers and the signal reproducer, tuning mechanism for each receiver, operating means for the tuning mechanisms, a selector for selecting the receiver to be tuned, and remote control means located in proximity to the signal reproducer and serving, when actuated, to control over said signal transmission line the operation of said selector and said operating means.

40 In testimony whereof I have affixed my signature.

DR. ALFRED RISTOW.
